[57] **CLAIM**

The ornamental design for a combined fuel, air, oil and windshield washer fluid dispensing unit with washing facilities, as shown and described.

DESCRIPTION

FIG. 1 is a front perspective view from above of a combined fuel, air, oil and windshield washer fluid dispensing unit with washing facilities embodying my new ornamental design; and.

FIG. 2 is a rear perspective view from above of the multi-purpose utility station.

1 Claim, 1 Drawing Sheet

Fig.1.

Fig.2.

UNITED STATES PATENT AND TRADEMARK OFFICE
CERTIFICATE OF CORRECTION

PATENT NO. : Des. 392,291

DATED : March 17, 1998

INVENTOR(S) : Alvern et al.

It is certified that error appears in the above-identified patent and that said Letters Patent is hereby corrected as shown below:

On the title page item [57],

Under "DESCRIPTION", lines 5-6, "FIG. 2 is a rear perspective view from above of the multipurpose utility station." should read --FIG. 2 is a rear perspective view from above of the combined fuel, air, oil, and windshield washer dispensing unit with washing facilities.--

Signed and Sealed this

Twenty-first Day of July, 1998

Attest:

Attesting Officer

BRUCE LEHMAN
